J. KLEIN

PISTON CLEANING TOOL

Filed April 13, 1927

Fig. 1.

UNITED STATES PATENT OFFICE.

JUAN KLEIN, OF ST. LOUIS, MISSOURI.

PISTON-CLEANING TOOL.

Application filed April 13, 1927. Serial No. 183,537.

This invention relates to a tool for cleaning the grooves of pistons, particularly of the internal combustion engine type, in which piston rings are employed. The tool is also 5 adapted to clean the sides of the pistons, and for this purpose a detachable knife or scraper blade is secured to the tool. It is an object of the invention to provide a spring-pressed and slidable scraper blade 10 holder and this holder receives a pair of blades which not only cleans the bottom surface of the piston ring groove but also cleans the sides thereof. It is a further object to provide an adjustable mounting for one of 15 the blades, so that they can be adjusted to fit any width of the groove. A still further object resides in the construction of the detachable blades.

Further objects will be apparent from the 20 following specification, taken in connection with the accompanying drawing, in which:

Figure 1 is a front view of the cleaning tool shown in position on a piston,

Fig. 2 is a side view of the outer or U- 25 shaped portion of the tool,

Fig. 3 is a side view of one of the scraper blades and its holder,

Fig. 4 is a side view of the other scraper 30 blade,

Fig. 5 is a front view of the blade for cleaning the sides of the piston,

Fig. 6 is a side view of the blade of Fig. 5, and

Fig. 7 is a front view of the connecting 35 member.

The tool comprises two main parts, one of which is the encircling member 1 and the other is the scraper blade holder 2. The member 1 comprises an elongated U-shaped portion or operating handle 3 of any suitable flat metal such as brass, cold rolled steel, etc., and the ends are directed outwardly at 4 and provided with circular portions 5. The ends of the circular portions are secured in spaced relation by means of a spacing tube 6 through which a rod 7 passes which secures the straight sections 8. A curved bearing member 9 is provided between the parts 5 and 8. The parts 3, 4, 5, 8 and 9 are preferably made integral and are maintained in spaced relation by the tube 6 at the top end and a connecting or guide member 10 at approximately inter-

mediate the ends. The other end comprises the bottom of the U as indicated at 11.

The holder 2 is slidably mounted in the member 1 on the connecting member 10. This member 10 is suitably secured in the member 1 by riveting as indicated at 11'. The holder is provided with slots 12 by which it slides on the connecting member 10 and in order to urge it outwardly out of the U-shaped portion a spring 13 is secured at one end to the bent portion 36 of the holder and the other end in the perforation 14 in the connecting member. As clearly shown in Fig. 1, if the tool is not in use the spring will force the holder outwardly to the limit of the slot, but if it is desired to insert the tool on the piston the holder is pushed inwardly against the force of the spring and when in position the spring will urge the holder outwardly so that the blades will be forced against the piston or into the grooves as the case may be.

The end of the holder is provided with a pair of detachable blades or scrapers 15 and 16. Each blade is provided with an outer cutting edge 17 and a side cutting edge of which 18 indicates the edge for fixed blade 16 and 19 for the adjustable blade 15. Also each blade is provided with a perforation of which the perforation 20 in blade 15 is elongated and the perforation 21 in blade 16 is circular. A screw 22 passes through the perforations in the blades and through the shank 23 of the holder and a winged nut 24 on the end thereof secures the blades in position. In order that the blades may be held rigid and at the same time parallel to the axis of the piston a pin 25 is provided for each blade which fits in a groove in the shank and in the blade.

The blades are mounted on the shank so that the cutting edge 19 shall contact on one side of the groove 26 of piston 27 as for instance the lower side 28 and edge 18 contacts with the upper side 29. The edges 17 contact with the bottom 30 of the groove. When it is desired to adjust the blades to accommodate a larger or smaller width groove the wing nut 24 is loosened and the blade 15 is moved laterally, due to the elongated perforation 20, until the desired width of the blades with respect to each other is reached, whereafter the winged nut is

tightened to maintain the blades in adjusted position. By removing the nut from the screw and pulling the screw out of the perforations the blades may be removed to be sharpened or renewed.

The use of the tool can easily be seen from Fig. 1 which shows the tool in the act of cleaning and scraping the ring groove 26. The spring 13 forces the holder outwardly 10 and the blades contact in the grooves while the bearing members 9 contact with and slide on the outer side of the piston. By turning the tool counter clockwise the edges of the blades will clean and scrape the 15 carbon from the groove.

For the purpose of cleaning the side of the piston a blade 31 having an edge 32 is mounted on the holder by means of the lugs 33 which are secured to the blade. The 20 same rotary motion of the tool will scrape and clean the side of the piston, the tool assuming the same operative position. Also mounting of the tool over the piston and removal therefrom is the same as when 25 cleaning the groove. Blade 31 is mounted between blades 15 and 16, the shank 23 being of the same thickness as lugs 33. The distance between lugs 33 is the same as the width of the scraper blade holder 2.

30 I claim as my invention:—

1. A piston cleaning tool comprising an encircling member having an operating handle; a holder slidably mounted in said handle; and a pair of blades mounted on 35 said holder one blade adjustable with relation to the other, and which are adapted to clean and scrape the piston ring grooves.

2. A piston cleaning tool comprising an encircling member having an operating handle; a spring-pressed holder slidably mounted in said handle; and a fixed blade 40 and an adjustable blade mounted on said holder which are adapted to clean and scrape the piston ring grooves.

45 3. A piston cleaning tool comprising an encircling member having an operating handle and curved bearing members adapted to contact with and bear against the side of the piston; a holder slidably mounted in said handle; and a cleaning blade mounted on 50 said holder adapted to clean and scrape the piston ring grooves.

55 4. A piston cleaning tool comprising an encircling member having an operating handle and curved bearing members adapted to contact with and bear against the side of the piston; a holder slidably mounted in said handle; and a fixed blade and an adjustable cleaning blade mounted on 60 said holder adapted to clean and scrape the piston ring grooves.

65 5. A piston cleaning tool comprising an encircling member having an operating handle and curved bearing members adapted to contact with and bear against the side of

the piston; a spring-pressed holder slidably mounted in said handle; and a fixed blade and an adjustable cleaning blade mounted in said holder adapted to clean and scrape 70 the piston ring grooves.

75 6. A piston cleaning tool comprising an encircling member having an operating handle; a guide member secured in said handle; a holder slidably mounted in said handle and on said guide member; and cleaning and scraping means mounted on 80 said holder adapted to clean and scrape the piston ring grooves.

85 7. A piston cleaning tool comprising an encircling member having an operating handle; a guide member secured in said handle; a holder slidably mounted in said handle and having slots therein, said holder sliding on 90 said guide member by means of the slots; and cleaning and scraping means mounted on said holder adapted to clean and scrape the piston ring grooves.

95 8. A piston cleaning tool comprising an encircling member having an operating handle; a guide member secured in said handle; a holder slidably mounted in said handle and having slots therein, said holder sliding on 100 said guide member by means of the slots; and a fixed blade and an adjustable cleaning blade mounted on said holder adapted to clean and scrape the piston ring 105 grooves.

110 9. A piston cleaning tool comprising an encircling member having an operating handle and curved bearing members adapted to 100 contact with and bear against the side of the piston; a guide member secured in said handle; a spring-pressed holder slidably mounted in said handle and having slots therein, said holder sliding on 105 said guide member by means of the slots; and adjustable cleaning and scraping means mounted on said holder adapted to clean and scrape the piston ring 115 grooves.

120 10. A piston cleaning tool comprising an encircling member having an operating handle; a guide member secured in said handle; a holder slidably mounted in said handle and having slots therein, said holder sliding on 115 said guide member by means of the slots; a spring, one end of which is secured to the holder and the other end to the guide member to urge the holder outwardly against the piston; and cleaning and scraping means mounted on said holder adapted to clean and scrape the piston ring 120 grooves.

125 11. A piston cleaning tool comprising an encircling member having an operating handle and curved bearing members adapted to contact with and bear against the side of the piston; a guide member secured in said handle; a holder slidably mounted in said handle and having slots therein, said holder sliding on 130 said guide member by means of the slots; a spring, one end of which is

secured to the holder and the other end to the guide member to urge the holder outwardly against the piston; and a pair of cleaning and scraping blades adjustably mounted relative to each other on said holder adapted to clean and scrape the piston ring grooves.

12. A piston cleaning tool comprising an encircling member having an operating handle and curved bearing members adapted to contact with and bear against the side of the piston; a guide member secured in said handle; a holder slidably mounted in said handle and having slots therein, said holder sliding on said guide member by means of the slots; a spring, one end of which is secured to the holder and the other end to the guide member to urge the holder outwardly against the piston; a pair of cleaning and scraping blades adjustably mounted relative to each other on said holder adapted to clean and scrape the piston ring groove; and means on the blades and the holder to maintain the blades rigid and parallel to each other.

13. A piston cleaning tool comprising an encircling member; and a fixed blade and an adjustable blade mounted in said member, each blade having two cutting edges one of which is on the end and the other on the side to clean and scrape the bottom and sides of the piston ring groove.

14. A piston cleaning tool comprising an encircling member; and a fixed blade and an adjustable blade mounted in said member, each blade having two cutting edges one of which is on the end and the other on the side and the blades being mounted so that a side cutting edge shall be on each side of the assembled pair of blades to clean and scrape the bottom and sides of the piston ring groove.

15. A piston cleaning tool comprising an

encircling member; and a pair of blades mounted in said member, each blade having two cutting edges one of which is on the end and the other on the side and the blades being mounted so that a side cutting edge shall be on each side of the assembled pair of blades to clean and scrape the bottom and sides of the piston ring groove, and one of the blades having an elongated perforation therein so that it may be adjusted laterally with respect to the other blade.

16. A piston cleaning tool comprising an encircling member; a pair of blades mounted in said member, each blade having two cutting edges one of which is on the end and the other on the side and the blades being mounted so that a side cutting edge shall be on each side of the assembled pair of blades to clean and scrape the bottom and sides of the piston ring groove, and one of the blades having an elongated perforation therein so that it may be adjusted laterally with respect to the other blade; and a screw and winged nut for tightly clamping the blades together in the adjusted position.

17. A piston cleaning tool comprising an encircling member having an operating handle; a spring-pressed holder slidably mounted in said handle; a pair of blades mounted in said holder, each blade having two cutting edges one of which is on the end and the other on the side and the blades being mounted so that a side cutting edge shall be on each side of the assembled pair of blades to clean and scrape the bottom and sides of the piston ring groove, and one of the blades having an elongated perforation therein so that it may be adjusted laterally with respect to the other blade; and a screw and winged nut for tightly clamping the blades together in the adjusted position.

In testimony whereof I affix my signature.

JUAN KLEIN.
